UNITED STATES PATENT OFFICE

JOHN E. MOORE, OF CHICAGO, ILLINOIS, ASSIGNOR TO STANDARD OIL COMPANY, OF WHITING, INDIANA, A CORPORATION OF INDIANA

LIQUID-SEALED RELIEF VALVE

Application filed May 14, 1928. Serial No. 277,779.

This invention relates to liquid sealed relief valves and will be readily understood from the following description, taken in conjunction with the accompanying drawing, in 5 which—

Figure 1 is an elevational view, partly in section, of a preferred form of relief valve; and

Fig. 2 is a longitudinal sectional view on a 10 plane passing through the center of the device.

Referring to the drawing, 10 is a vertical outlet connected by conduit 11 to the vapor space of a storage system for hydrocarbon 15 oils. The outlet 10 is surrounded by walls 12 and 13, standing in spaced relation thereto, so as to constitute therearound a receptacle 14 for a suitable sealing liquid, such as water, seal oil, or the like. The walls 12 pref- 20 erably flare outwardly in the upward direction, as shown in the drawing.

Above the outlet 10 is pivotally mounted an inverted cup 15 having sides 16 which depend downwardly into sealing liquid main- 25 tained in the receptacle 14. The cup 15 is provided with trunnions 17 which are engaged by suitable brackets mounted on the sides 13 of the receptacle 14. The trunnions 17 are laterally displaced from the center of 30 pressure of the inverted cup 15, and a suitable weight 18 is provided on the shorter side of the cup so that it is normally in balanced condition. The sides 16 of the cup 15 may be cut away, as shown at 25, so that the open- 35 ing of the seal between said sides and the sealing liquid in receptacle 14 may be gradual.

The inverted cup 15 is provided with suitable weights for the purpose of preventing rotation of the cup on its axis until it is subjected to a certain excess of pressure on one 40 side or the other, such excess pressure being predetermined to ensure the safety of the storage system. Such weights may suitably be constituted by metal strips 19 carried on the upper surface of the inverted cup 15 and provided with depending portions 20, which extend into the sealing liquid in receptacle 14 and are provided at their lower ends with pressure plates 21 which offer resistance to 45 rapid movement through said liquid.

The metal strips 19, 20 are maintained in operative position by strips 22 which are connected thereto and which loosely engage the trunnions 17. This specific means for preventing rocking and for delaying rotation of 55 the inverted cup is described and claimed in application, Serial No. 229,990, now Patent 1,747,810, filed October 31, 1927, by Harold V. Atwell, and is not claimed broadly herein.

From the upper face of the inverted cup 15 depends an open conduit 23. The axis of this conduit is preferably located in the vertical plane of the trunnions 17. The lower end of the conduit 23 extends into a trough 60 24 supported in suitable manner from the walls of the outlet 10. The trough 24 is preferably a segment of a cylinder, the axis of which coincides with that of the trunnions 17. The lower end of the conduit 23 is so 65 cut that it extends into proximity to the curved wall of the trough 24. The trough 24 may contain mercury or other suitable sealing liquid.

A suitable cover 26, which permits free 70 access to the atmosphere, is applied over the receptacle 14.

The operation is as follows: When the pressure in the vapor system attains the predetermined excess pressure, such excess pressure 75 acting upon the longer side of the inverted cup 15 causes the same to rotate in the clockwise direction, with reference to the drawing, such excess pressure being sufficient to enable the cup to raise the weight system 80 19, 20 on the left hand side of the cup. During such movement, the plate 21 passing through the said sealing liquid, prevents undue oscillation. The weight system 19, 20 on 85 the right hand side of the cup remains stationary, the plate 21 thereof bearing upon the bottom of the liquid sealed chamber around the outlet 10. When the cup 15 rotates in the manner described, the conduit 23 emerges gradually from the sealing liquid 90 in trough 24 and permits the escape of vapor through said conduit until the excessive pressure within the system is relieved, whereupon the cup 15 returns to normal position 95 100

and the conduit 23 is again sealed by the liquid in the trough 24.

When the atmospheric pressure exceeds the pressure in the vapor system by the predetermined amount, the excess pressure, acting upon the longer side of the cup 15, causes the same to rotate in counter-clockwise direction, with reference to the drawing, and the conduit 23 emerges from the sealing liquid in the trough 24 so that air passes into the system through said conduit until the excessive vacuum in the vapor system is relieved, whereupon the cup 15 returns to its normal position and the conduit 23 is again sealed by the liquid in the trough 24.

The sealing liquid around the outlet 10 may be regulated in quantity so that the sides 16 of the cup 15 may emerge from the sealing liquid in receptacle 14, when said cup rotates in either direction. By adjusting the level of said sealing liquid, the partial emergence of such sides may be caused to occur simultaneously with, before or after the opening of the seal of the conduit 23. If desired, venting may be caused to occur exclusively through the conduit 23.

Although the present invention has been described in connection with the details of a specific embodiment thereof, it must be understood that such details are not intended to be limitative upon the scope of the invention, except in so far as they are included in the accompanying claims.

35 I claim:

1. A liquid sealed relief valve comprising a sealed member adapted to be oscillated by excess pressure thereon, a tubular member carried by the first said member, and means 40 for containing sealing liquid for said tubular member, said tubular member being adapted to withdraw from the liquid in said containing member when the first said member oscillates.

45 2. A liquid sealed relief valve comprising a sealed member adapted to be oscillated by excess pressure in either direction, a tubular member carried by said oscillating member, and a liquid container adapted to contain 50 liquid co-operating with the lower end of said tubular member in such manner that said tubular member withdraws from said liquid when it is oscillated by said oscillating member.

55 3. A liquid sealed relief valve comprising an inverted cup pivoted on an axis laterally displaced with respect to its center of pressure, a tubular member extending 60 downwardly from the upper surface of said cup, and a trough for holding sealing liquid in co-operative relationship with the lower end of said tubular member, whereby said tubular member is adapted to rotate out of 65 contact with said liquid for the purpose of

permitting gases to pass from one side of the inverted cup to the other.

4. A liquid sealed relief valve comprising a vapor outlet, walls for maintaining a body of liquid therearound, an inverted cup pivotally mounted over said outlet on an axis displaced laterally with respect to its center of pressure, said cup being provided with sides adapted to depend into said sealing liquid, an open tubular member extending from the top of said inverted cup, and a trough located below said tubular member and containing sealing liquid adapted to co-operate with the lower end of said tubular member. 70 75

5. A liquid sealed relief valve comprising a vapor outlet, walls for maintaining a body of liquid therearound, an inverted cup pivotally mounted over said outlet on an axis displaced laterally with respect to its center of pressure, said cup being provided with sides adapted to depend into said sealing liquid, an open tubular member extending from the top of said inverted cup, a trough located 80 85 below said tubular member and containing sealing liquid adapted to co-operate with the lower end of said tubular member, and means for preventing rotation of said cup until a predetermined excess of pressure exists on one side or the other of said cup. 90 95

6: A liquid sealed relief valve comprising a sealed member adapted to be oscillated by excess pressure in either direction, a single vapor pipe below said member, a tubular member carried by the first said member, 100 and means for containing sealing liquid for said tubular member, said tubular member being adapted to withdraw from the liquid in said containing member when the first said member oscillates. 105

In testimony whereof, I have hereunto set my hand this 27th day of April, 1928.

JOHN E. MOORE.
